UNITED STATES PATENT OFFICE.

OSCAR A. SMITH, OF CLEVELAND, OHIO, ASSIGNOR TO THE NATIONAL-ACME MANUFACTURING COMPANY, OF CLEVELAND, OHIO, A CORPORATION OF OHIO.

MACHINE FOR CASTELLATING NUTS.

1,010,450.

Specification of Letters Patent.

Patented Dec. 5, 1911.

Application filed October 8, 1909. Serial No. 521,662.

To all whom it may concern:

Be it known that I, OSCAR A. SMITH, a citizen of the United States, residing in Cleveland, in the county of Cuyahoga and State of Ohio, have invented certain new and useful Improvements in Machines for Castellating Nuts, of which the following is a specification.

This invention relates to machines for automatically forming a number of diametral slots in nuts or the like, sometimes termed castellated nuts for the purpose of being engaged by cotter pins to lock the nuts in position and prevent their becoming loose.

The object of the invention is to provide a machine of this character that will be entirely automatic in its operation, the nuts simply being placed in a hopper, from which they are fed into the machine for the proper slots to have cut and then are ejected.

In the accompanying drawings representing an embodiment of my invention, Figure 1 shows the machine in end elevation. Fig. 2 is a side elevation of the machine, certain parts being broken, to show the interior construction. Fig. 3 is a section enlarged on the line 3-3 indicated in Fig. 2. Fig. 4 is a fragmentary view enlarged showing the three cutters, and Fig. 5 shows one of the sockets for receiving the nut.

On a suitable frame F is a casing 6 in which rotates a head 7. In one face of the head is a circular series of sockets, these being shown equidistant, in each of which is secured a bushing 8 shown separately in Fig. 5, which bushing is shown as having a socket portion 9 of the proper shape to receive the nut, which is shown hexagonal for such form of nut, the socket being preferably of slightly less depth than the height or thickness of the nut, so that the saw or turret will not engage the face of the bushing.

Any of the usual or preferred means for indexing the head used in turret lathes and automatic machines may be employed, by which the head is intermittently rotated for an angular distance equal to the angular distance apart of the sockets for the nuts. By this means at each advance each of the nut sockets is shifted to the position of the preceding one, whereby they can be successively operated upon by the slotting tools as advanced. The present machine is shown pro-

vided with a driving shaft 10 that may receive its power through a worm wheel 11 and worm 12 from a driving shaft 13, by which means the shaft 10 is slowly rotated. This shaft is shown as provided with a segment gear 14 that engages a gear 15 fast on the head, the segment gear being of such length as to advance the head one-sixth of a revolution at each period of engagement, and obviously the head will not be moved during the balance of the revolution of the segment, and during which time it is stationary to receive the operation of the cutters on the nuts.

Suitable locking means may be provided if desired to retain the head in precisely the proper position each time it is thus advanced one-sixth of a revolution. The head is provided with six sockets 16, each of which will be brought to register with a sliding bolt 17 after engagement of the segment 14 with the gear. A bent lever 18 pivoted on a bracket 19 has one end engaging a socket 20 on the bolt 17, and the bolt is normally retained in locking position with the head by a spring 21. A disk 22 on the shaft 10 carries a roller 23 that at one position of the rotation will engage the extremity of the lever 18 and swing it to withdraw the bolt 17 and hold it out of engagement with the socket portions 16 of the head; which roller is positioned relative to the segment gear 14 so that the bolt is withdrawn and retained until the segment gear has advanced the head the unit distance, whereupon the bolt is released and will be drawn inward by the spring 21 to engage the socket and again lock the head.

The nuts are fed downward by suitable means and inserted into the bushings after each advance of the head. A chute 24 is shown through which the nuts are fed downward by gravity and in their lowermost position therein will be opposite one of the sockets, the socket 9^a as shown in Figs. 1 and 3.

A slide 25 is mounted on the bed 26 of the frame to move parallel with the axis of the head and is shown as operated by a roller 27 on the slide engaged alternately by diagonal straps 28 and 29 carried by the drum 30 fast on the shaft 10, by which means the slide is reciprocated intermittently once for each revolution of the shaft 10, the head being advanced one-sixth of a revolution by each

revolution of the shaft 10. Therefore the slide will move up and back once each time the head is indexed to advance the nuts in the bushings. The slide 25 carries in suitable bearings three vertical shafts 31, 32 and 33 having cutters 34, 35 and 36 respectively; and these cutters are located in axial alignment with the axes of the three socket members 9 that are in the uppermost positions, as indicated in Figs. 1 and 3. Consequently, when the slide is advanced the cutters will approach the socket members respectively, and they will engage the respective nuts that may be located or held therein. The cam straps 28 and 29 are so arranged that the slide will be advanced a sufficient distance to cause the three cutters, that are rotated by suitable means, to make a diagonal cut or slot in the nuts held in the sockets 9.

It will be observed that the three cutters are each rotated in a horizontal plane. Suitable means are provided for rotating these cutters, each of their shafts being provided with bevel gears 37, 38 and 39 meshing with bevel gears 40, 41 and 42 mounted on a shaft 43, horizontally supported in the slide. This shaft is driven by suitable means such as a gear 44 meshing with a gear 45 on a stub shaft 46. The latter is shown as driven by a pulley 47, which may have an overhead belt thereon, not shown, that will constantly drive it during its horizontal reciprocation by the movement of the slide. By this means the cutters will be constantly driven.

The nuts are fed in the position indicated by 9^a in Fig. 3. The next advance of the head will bring this nut to the position 9^b, where it will be operated upon by the first cutter and receive a horizontal slot. The next advance of the head will bring this nut to the position 9^c, and as the nut has been given a circular movement of one-sixth of a revolution, the slot now cut in it by the uppermost cutter 35 will make an angle of sixty degrees with the slot previously cut and obviously both of these slots will be diametral. The next advance of the head will bring the nut to the position 9^d and the slot cut at this position will make an angle of sixty degrees with the slot cut in the position 9^c for the reason that the nut has been again swung through an arc of sixty degrees to the horizontal. Therefore the nut will now have received three slots that are diagonal and sixty degrees apart, or in other words six radial slots will be cut in the face of the nut. Upon a nut being fed in between each advance of the head, and being suitably ejected after passing the position 9^d, it is evident that there are three slots cut at each index movement of the head.

A plunger 50 slides in a socket 51 in the slide 25 and is pressed inwardly by a spring 52, to engage the lowermost nut in the chute 53 upon the slide 25 being advanced, where-

by this nut will be shifted into the socket 9^a, that is in registering position. The advance of the head will bring the three uppermost sockets adjacent a fan plate 53 fast on rod 54 slidably in the head 7, that is pivoted at the rear to a lever 57 swinging on a bracket 58. The lever 57 is connected with the machine by a spring 59 and presses a roller 60 against a cam 61 on the shaft 10. This cam normally engages the roller to position the fan plate 53 to hold the nuts in their sockets; the plate 53 being provided with slots 62, 63 and 64, through which the cutters respectively freely pass to engage the nuts that are held by the plate in their respective sockets. Thereupon the plate is released and drawn slightly back by the spring to permit indexing of the head when the plate again engages the nuts to lock them in the sockets.

To automatically eject the nuts, when in the position 9^a, suitable means are provided, comprising plungers 65 mounted in sockets opposite each of the bushings 9 and passing therethrough, these plungers being engaged by springs 66 to project slightly to the rear, but having their forward ends not extending into the socket portion of the bushing for the nuts. As each of these plungers reaches the position of the bushing 9^a it engages a cam plate 67 fast on the frame for the head, and is thereby advanced against the pressure of its spring to engage and eject the nut held in the bushing. As soon as the plunger leaves this position, it is disengaged by the cam plate and returns to normal position by the reaction of its spring. By this construction it will be seen that the nuts are automatically fed from the chute into the bushings of the head, and when the head is advanced the bushing is carried upward, and the nut is engaged by the fan plate as soon as the head is again arrested. In this position the nut has the first diagonal slot cut therein. During this operation the next nut is advanced into its bushing. At the next indexing of the head the first nut is advanced to the second position for slotting while the second nut is advanced to its first position for slotting; and the third nut is now fed into the bushing. The advancement of the cutters will cause the first nut to receive the second slot that is diagonal and at sixty degrees with the first slot cut; while the second nut fed will receive its first slot, and the third nut will be fed into a bushing. The next step of indexing will bring the first nut into position to receive its third slot that will be at sixty degrees to the second slot, while the second nut will receive its second slot and the third nut its first slot, the fourth nut being now fed into the bushing. This first nut will now have three slots that are diametral and sixty degrees separated, which is the same

as six radial slots sixty degrees apart. The next indexing will bring the first nut that has now been entirely castellated to the position where it will be automatically ejected.

5 In this same manner at each step there will be one nut fed, three nuts will be slotted, and one entirely slotted nut will be ejected from the machine.

Having thus described my invention, I 10 claim:

1. In an automatic nut castellating machine, the combination of an intermittently revoluble turret, means for automatically indexing it, a series of blank holding means 15 carried by the turret, a reciprocatory slide, a plurality of shafts carried by said slide and located in vertical planes with the axes thereof spaced apart to correspond with the distance between the axes of the blank holding means of said turret, means for rotating said shafts, slotting tools carried by the shafts, and means for automatically reciprocating the slide intermediate each indexing of the turret whereby a plurality of blanks 20 will be slotted simultaneously with the slot of one blank located at an angle to that of another.

2. In an automatic nut castellating machine, the combination of an intermittently revoluble turret, means for automatically indexing it, a series of blank holding means carried by the turret, a reciprocatory slide, a plurality of shafts carried by said slide and located in vertical planes with the axes 25 thereof spaced apart to correspond with the distance between the axes of the blank holding means of the turret, means for rotating said shafts, slotting tools carried by the shafts and located in parallel planes, and 30 means for automatically reciprocating the slide intermediate each indexing of the turret whereby a plurality of blanks will be slotted simultaneously with the slot of one blank located at an angle to that of another.

45 3. The combination of a frame, a head rotatable in the frame and carrying a circular series of bushings parallel to the axis of the head, means for indexing the head around 50 to advance each bushing a distance equal to their distance apart, a plurality of slotting tools arranged so that they can be advanced to each engage a nut in one of the said bushings in the head, means for reciprocating 55 the tools between successive movements of the head, whereby each nut in a bushing is successively operated upon by the said plurality of tools, the tools being arranged in parallel planes whereby the advancement of 60 the nuts by the head will cause the slots to have angular positions relatively to one another, a chute for the nuts, means for feeding the nuts into the bushings between each advance of the head, means for ejecting the 65 nuts after being engaged by the tools, a plate

shiftably supported adjacent the bushings for the nuts in their position for engagement by the tools, and having openings permitting passage of the tools for engagement with the nuts, means for shifting the plate to engage 70 and clamp the nuts in the bushings, and means for shifting the plate in the opposite direction when the head is advanced by the indexing means.

4. In an automatic nut castellating machine, the combination of an intermittently revoluble turret, means for automatically indexing it, a circular series of blank holding means carried by the turret, a reciprocatory slide, a series of three shafts carried by said 75 slide and located in vertical planes with the axes thereof spaced apart to correspond with the distance between the axes of the blank holding means of the turret, means for rotating said shafts, slotting tools carried by the 80 shafts one located in a horizontal plane parallel with its companion tools, and means for automatically reciprocating the slide intermediate each indexing of the turret whereby a series of three blanks will be slotted simultaneously with the slot of one blank located 85 at an angle to that of another blank.

5. In an automatic nut castellating machine, the combination of an intermittently revoluble turret member, means for automatically indexing it, a circular series of blank holding means carried by the turret member, a reciprocatory slide member, a series of slotting tools carried by the slide member and located in circular arrangement 90 corresponding with the circular series of blank holding means of the turret member with one tool in a horizontal plane parallel with its companion tools, and means for automatically reciprocating one of said members intermediate each indexing of the turret member whereby a plurality of blanks will be slotted simultaneously with the slot of one blank located at an angle to those of its companion blanks.

6. In an automatic nut castellating machine, the combination of an intermittently revoluble turret, means for automatically indexing it, a circular series of blank holding means carried by the turret, a reciprocatory 100 slide, a series of slotting tools carried by said slide and located in circular arrangement corresponding with the circular series of blank holding means carried by the turret with one tool in a horizontal plane parallel 105 with its companion tools, and means for automatically reciprocating the slide intermediate each indexing of the turret whereby a plurality of blanks will be slotted simultaneously with the slot of one blank located 110 at an angle to those of its companion blanks.

7. In an automatic nut castellating machine, the combination of an intermittently revoluble turret, means for automatically indexing it, a series of blank holding means 115

carried by the turret, means for automatically feeding blanks successively to the blank holding means of the turret, means for automatically ejecting the blanks, a reciprocatory slide, a plurality of slotting tools carried by the slide and located in parallel horizontal planes and effective to slot a plurality of blanks simultaneously with the slot of one blank at an angle to that of another blank, and means for automatically reciprocating the slide intermediate each indexing of the turret.

8. In an automatic nut castellating machine, the combination of an intermittently revoluble turret, means for automatically indexing it, a series of blank holding means carried by the turret, means for automatically feeding blanks successively to the blank holding means of the turret, means for automatically ejecting the blanks successively, a reciprocatory slide, a series of vertically located shafts carried by said slide, means for rotating said shafts, a slotting tool carried by each of said shafts adjacent to its lower end and rotatable one in a horizontal plane parallel with its companion tools whereby a plurality of blanks will be slotted simultaneously with the slot of one blank at an angle to that of another blank, and means for automatically reciprocating the slide intermediate each indexing of the turret.

9. In an automatic nut castellating machine, the combination of an intermittently revoluble turret, means for automatically indexing it, a series of blank holding means carried by the turret, means for automatically feeding blanks successively to the blank holding means of the turret, automatically operative means located to move toward and from the face of the turret for clamping the blanks in position in the blank holding means carried by the turret, means for shifting said means, a reciprocatory slide, a plurality of slotting tools carried by the slide and located to slot a plurality of blanks simultaneously with the slot of one blank at an angle to that of another blank, and means for automatically reciprocating the slide intermediate each indexing of the turret.

50 10. In an automatic nut castellating machine, the combination of an intermittently revoluble turret, means for automatically indexing it, a series of blank holding means carried by the turret, means for automatically feeding blanks successively to the blank holding means of the turret, automatically operative means located to move toward and from the face of the turret for clamping the blanks in position in the blank holding means carried by the turret and comprising a plate, means for shifting said plate, a reciprocatory slide, a plurality of slotting tools carried by the slide and located to slot a plurality of blanks simultaneously with the slot of one blank at an angle to that of another blank.

65 11. In an automatic nut castellating machine, the combination of an intermittently revoluble turret, means for automatically indexing it, a series of blank holding means carried by the turret, means for automatically feeding blanks successively to the blank holding means of the turret, automatically operative means located to move toward and from the face of the turret for clamping the blanks in position in the blank holding means carried by the turret and comprising a plate, means for shifting said plate, a reciprocatory slide, a plurality of slotting tools carried by the slide and located to slot a plurality of blanks simultaneously with the slot of one blank at an angle to that of another blank.

another blank, and means for automatically reciprocating the slide intermediate each indexing of the turret.

11. In an automatic nut castellating machine, the combination of an intermittently revoluble turret, means for automatically indexing it, a series of blank holding means carried by the turret, means for automatically feeding blanks successively to the blank holding means of the turret, automatically operative means located to move toward and from the face of the turret for clamping the blanks in position in the blank holding means carried by the turret and comprising a plate having openings for the passage of the slotting tools, means for shifting said plate, a reciprocatory slide, a plurality of slotting tools carried by the slide and located to slot a plurality of blanks simultaneously with the slot of one blank at an angle to that of another blank, and means for automatically reciprocating the slide intermediate each indexing of the turret.

12. In an automatic nut castellating machine, the combination of an intermittently revoluble turret, means for automatically indexing it, a circular series of blank holding means carried by the turret, means for automatically feeding nuts to the blank holding means of the turret, a plate shiftably supported adjacent to the face of the turret for clamping the nuts in the blank holding means of the turret, means for automatically shifting the plate toward and from the blanks, a reciprocatory slide, a plurality of shafts carried by said slide and located in parallel planes with the axes thereof spaced apart to correspond with the distance between the axes of the blank holding means of the turret, means for rotating said shafts, slotting tools carried by the shafts, and means for automatically reciprocating the slide intermediate each indexing of the turret whereby a plurality of blanks will be slotted simultaneously with the slot of one blank located at an angle to that of another.

13. In an automatic nut castellating machine, the combination of an intermittently revoluble turret, means for automatically indexing it, a series of blank holding means carried by the turret; a chute for feeding blanks successively to the blank holding means of the turret, a reciprocatory slide, a spring controlled plunger carried by said slide for pushing nut blanks from the chute into the blank holding means of the turret, a plurality of slotting tools carried by the slide and located in parallel horizontal planes and effective to slot a plurality of blanks simultaneously with the slot of one blank located at an angle to that of another, and means for automatically reciprocating the slide intermediate each indexing of the turret.

14. In an automatic nut castellating ma-

chine, the combination of an intermittently revoluble turret, means for automatically indexing it, a circular series of blank holding means carried by the turret, ejecting devices 5 likewise carried by the turret one for each of said blank holding means and comprising a series of plungers and means for successively operating the plungers one on each indexing of the turret, a reciprocatory slide, 10 means for reciprocating it, a blank carrying chute, means carried by the slide for feeding blanks successively from the chute to the blank holding means carried by the turret, and slotting means carried by the slide 15 and comprising a plurality of vertically located shafts spaced apart in parallel planes and rotatable slotting tools carried by said shafts and located in horizontal parallel planes and effective to slot a plurality of 20 blanks simultaneously with the slot of one blank located at an angle to that of another. 15. In an automatic nut castellating machine, the combination of an intermittently revoluble turret, means for automatically indexing it, a circular series of blank holding means carried by the turret, ejecting devices 25 likewise carried by the turret one for each of said blank holding means and comprising a series of plungers and means for successively operating the plungers one on each indexing of the turret, a reciprocatory slide, means for reciprocating it and including a cam shaft, a blank carrying chute, means 30 carried by the slide for feeding blanks successively from the chute to the blank holding means carried by the turret, slotting means carried by the slide and comprising a plurality of vertically located shafts spaced 35 apart in parallel planes and rotatable slotting tools carried by said shafts and located in horizontal parallel planes and effective to slot a plurality of blanks simultaneously with the slot of one blank located at an angle to that of another, and means also actuated by said cam shaft for clamping the nut blanks in the blank holders of the turret. 40 16. In an automatic nut castellating machine, the combination of an intermittently revoluble turret, means for automatically indexing it, a circular series of blank holding means carried by the turret, ejecting devices likewise carried by the turret one for each of said blank holding means and comprising a series of plungers and means for successively operating the plungers one on each indexing of the turret, a reciprocatory slide, 45 means for reciprocating it, a blank carrying chute, means carried by the slide for feeding blanks successively from the chute to the blank holding means carried by the turret, and slotting means carried by the slide and comprising a plurality of shafts spaced apart in parallel planes and rotatable slotting tools carried by said shafts and located in horizontal parallel planes and effective to slot a plurality of blanks simultaneously with the slot of one blank located at an angle to that of another. 50 17. In an automatic nut castellating machine, the combination of an intermittently revoluble turret, means for automatically indexing it, a series of blank holding means carried by the turret, a reciprocatory slide, a plurality of shafts carried by said slide and located in parallel planes with the axes thereof spaced apart to correspond with the distance between the axes of the blank holding means of the turret, means for rotating said shafts, slotting tools carried by the 55 shafts and likewise located in parallel planes, means for automatically reciprocating the slide intermediate each indexing of the turret whereby a plurality of blanks will be slotted simultaneously with the slot of one blank located at an angle to that of another, means for simultaneously automatically clamping a plurality of nut blanks in the blank holders, and means for automatically operating it. 60 18. In an automatic nut castellating machine, the combination of an intermittently revoluble turret, means for automatically indexing it, a circular series of blank holding means carried by the turret, ejecting devices likewise carried by the turret one for each of said blank holding means and comprising a series of plungers and means for successively operating the plungers one on each indexing of the turret, a reciprocatory slide, means for reciprocating it, a blank carrying chute, means carried by the slide for feeding blanks successively from the chute to the blank holding means carried by the turret, and slotting means carried by the slide and comprising a plurality of shafts spaced apart in parallel planes and rotatable slotting tools carried by said shafts and located in parallel planes and effective to slot a plurality of blanks simultaneously with the slot of one blank located at an angle to that of another. 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
